Patented Aug. 6, 1974

232,295

SERVER FOR INSTANT COFFEE OR THE LIKE

Edward Vujnovic, 99 Ashland Ave.,
Buffalo, N.Y. 14222

Filed Feb. 5, 1973, Ser. No. 329,724

Term of patent 14 years

Int. Cl. D7—06

U.S. Cl. D7—58

Fig. 1.

Fig. 2.

Fig. 3.

Fig. 4.

Fig. 5.

FIG. 1 is a side elevational view of a server for instant coffee or the like, showing my new design;

FIG. 2 is a top plan view thereof;

FIG. 3 is an elevational view taken from the side opposite that of FIG. 1;

FIG. 4 is a bottom plan view thereof; and

FIG. 5 is a perspective view thereof.

I claim:

The ornamental design for a server for instant coffee or the like, substantially as shown.
